UNITED STATES PATENT OFFICE

145,878

DESIGN FOR A DESK UNIT OR THE LIKE

Fortunato S. Ajero, Chicago, Ill.

Application May 4, 1946, Serial No. 129,324

Term of patent 14 years

(Cl. D74—1)

To all whom it may concern:

Be it known that I, Fortunato S. Ajero, a citizen of the United States, residing at Chicago, in the county of Cook and State of Illinois, have invented a new, original, and ornamental Design for a Desk Unit or the Like, of which the following is a specification, reference being had to the accompanying drawing, forming part thereof.

In the drawing:

Figure 1 is a perspective view in closed position of a desk unit or the like showing my design;

Figure 2 is a perspective view of the same in an open position, showing the essential features thereof in full lines; and

I claim:

The ornamental design for a desk unit or the like, as shown and described.

FORTUNATO S. AJERO.
